UNITED STATES PATENT OFFICE.

RALPH N. HILL, OF BLOOMFIELD, NEW JERSEY, ASSIGNOR TO WESTERN ELECTRIC COMPANY, OF NEW YORK, N. Y., A CORPORATION OF ILLINOIS.

SELECTIVE SIGNALING SYSTEM.

1,136,337.

Specification of Letters Patent. Patented Apr. 20, 1915.

Application filed October 15, 1913. Serial No. 795,175.

To all whom it may concern:

Be it known that I, RALPH N. HILL, a citizen of the United States, residing at 42 Park avenue, Bloomfield, in the county of Essex and State of New Jersey, have invented a certain new and useful Improvement in Selective Signaling Systems, of which the following is a full, clear, concise, and exact description.

10 This invention relates to selective signaling systems for train despatching and like purposes, in which a plurality of waystations located upon a line may be selectively signaled from a sending or despatching station.

15 The object of this invention is to provide an efficient, convenient and reliable means for operating the signals at the waystations by ringing current supplied from the sending or despatching station.

20 In a system to which this invention is particularly adaptable, the waystation selectors are bridged across the line and an impulse sending relay located at the main or sending station is operated to intermittently connect a source of current to the line wires for operating the selectors.

25 In the application of this invention to this system, the apparatus is so combined and connected that after a circuit closing device located at a waystation has been conditioned to receive a signal, a circuit is closed at the main or sending station for applying an undulating current to the line 30 wires for signaling the waystation attendant.

35 In the drawing.—Figure 1 is a circuit diagram of a selective signaling system embodying this invention, and Fig. 2 is a fragmentary detail view of a selector showing the arrangement of the contact springs.

40 As shown in said drawings, A designates a sending or despatching station connected by means of line wires 5 and 6 with waystations B and C. Located at the despatching station A is an impulse transmitter 7 comprising a rotatable disk 8 provided with teeth 9 on its periphery, adapted as said disk 8 rotates, to close contacts 10, 11 for completing a circuit from a local battery 12 through the winding of an impulse relay 13. The operation of the impulse relay 13 intermittently connects and disconnects a battery 14 with the line wires 5 and 6 through armatures 15 and 16 and contact springs 17 and 18 of the impulse relay 13 to operate the selectors. Retardation coils 19, 20 and 21

connected in the line wires and a condenser 22 bridged across said line wires co-operate to smooth out the current impulses sent over the line for selecting purposes, so that there will be no disagreeable thump in any telephone receiver which may be bridged across the line during selection. A non-inductive resistance 23 normally in bridge of the line wires 5 and 6 through a contact 24 on the impulse 65 relay 13, is intermittently disconnected from and connected therewith by the operation of said impulse relay. This non-inductive resistance 23 forms a low resistance discharge path for the retardation coils 19, 20 and 21 70 and the condenser 22 so that the current impulses over the line will not be prolonged to an extent that will cause the sticking of the selector magnets. Bridged around contacts 15, 17 are a condenser 26 and a resistance 27 75 and around contacts 16, 18 are a condenser 28 and a resistance 29, which prevent sparking at said contacts 15, 17 and 16, 18 when the circuit from the battery 14 to the line wires 5 and 6 is broken at said contacts. 80

30 designates a despatcher's telephone set which is normally across the line wires 5 and 6 at the despatching station. The impulse transmitter 7 may be made adjustable by means of segments 31 and 32 adjustably 85 secured to one face of the disk 8 and adapted to vary the number of teeth effective for calling purposes. The periphery of the segment 32 is at a greater distance from the center of the disk 8 than the periphery of 90 the teeth 9 and segment 31, so that when it is engaged by the contact spring 10, the spring 11 is raised far enough to cause the engagement thereof with a spring 33 for completing a circuit from a battery 14 95 through the winding of an interrupter 34 and the primary of an induction coil 35 whose secondary is connected in the line wires. As the interrupter 34 is energized it attracts armature 36, thereby opening the 100 circuit through its winding, whereupon the armature 36 is retracted, closes the circuit and again permits the energization of the interrupter. In this way interrupted current is passed through the primary of the induction coil 35, and since there is direct current from the battery 14 on the line through the secondary of the induction, there is produced undulating current in the secondary thereof which passes over the line wires for 105 operating the signal at the waystation. Ringing current will therefore be on the line 110

as long as the spring 10 is in engagement with the surface of the segment 32 and the contact 11, 33 remains closed.

The selector at each waystation embraces a slow-acting magnet 40 hereinafter termed a holding magnet, a quick-acting magnet 41 hereinafter termed a stepping magnet and a ratchet wheel 42 adapted to be rotated in one direction under control of the holding and stepping magnets 40 and 41, and returned to normal by means of a coiled actuating spring 43. The holding and stepping magnets are connected in series in bridge of the line wires and control armatures 44 and 45 respectively. Carried by the armature 44 are two angularly disposed arms 46 and 47, the arm 46 being in engagement with a holding pawl 48, and the arm 47 being in engagement with a stepping pawl 49 carried by the armature 45. The movement of the armature 44, due to energization of the magnet 40, permits the pawls 48 and 49 to be moved into position to engage the ratchet wheel 42 by the action of springs 50 and 51 respectively. In series with the holding magnet 40 and the stepping magnet 41 is a non-inductive resistance 53. The value of this resistance 53 varies for each waystation, the different values thereof being such that the holding and stepping magnets at each waystation receive the same amount of current.

Referring now to the details of the selector, it will be noted that the ratchet wheel 42 carries two contact arms 60 and 61 adapted in the rotation of said ratchet wheel to be brought separately into engagement with a contact spring 62 located adjacent said ratchet wheel. The spring 62 is in mechanical engagement with the stepping armature 45 through a projecting arm 63 (see Fig. 2) on said spring, which engages an insulating button carried by said arm. The tension of said spring being in a direction to force it toward armature 45, said spring will partake of the motion of said armature during the stepping movement thereof. A second contact spring 64 mounted adjacent to the spring 62 and in line therewith, normally bears against an insulating pin 65 on the stepping armature 45 when the selector parts are in their normal or inoperative position, and against an insulating button 66 on the outer end of the arm 47 when the holding magnet 40 is energized and its armature 44 is in its attracted position. As shown in the drawing, the arm 61 carried by the ratchet wheel 42, is slightly longer than the arm 60 and is located slightly in advance of said arm 60. These arms are adapted to cooperate with the contact springs 62 and 64 in the following manner.

When the shorter contact arm 60 is brought into position to engage the contact spring 62, it pushes said contact spring away

from engagement with the armature 45 and the contact, made by the engagement of said arm 60 with said contact spring 62, completes a short circuit of the holding magnet 40. This causes the deenergizing of the holding magnet 40 and permits the armature 44 thereof to drop back to normal position. The contact spring 64 remains in contact with the arm 47 until it comes into engagement with the insulating pin 65. The relation of the arm 60 with respect to said pin 65 is such, however, that the spring 64 is stopped before it makes contact with the spring 62. If, however, the arm 61 is the one brought into contact with the spring 62, the relation of the parts will be changed. In this position of the parts, the engagement of the arm 61 with the spring 62 will complete the short circuit of the holding magnet 40 as in the former case, but the arm 61 being longer than the arm 60, the contact spring 62 will be held in a position beyond the outer end of the insulating pin 65, so that as the spring 64 follows the arm 47 forward upon the release of the holding magnet armature 44, said spring 64 will be brought into contact with the spring 62 and will close the normally open bridge, which includes an alternating current bell 67 and a condenser 68, thereby conditioning said bell circuit for operation when contact is made between springs 11 and 33 of the impulse transmitter 7. A resistance 69 is placed in a normally open bridge of the stepping magnet 41, so that as the alternating current bell 67 is operated, said resistance is intermittently placed in parallel with the stepping magnet 41, thereby causing an intermittent increase in flow of current on the line and furnishing an answer-back signal which will be heard through the dispatcher's receiver and notifying the dispatcher that the bell at the waystation is being operated.

Referring now to the operation of the selective signaling system embodying this invention, it will be assumed that the selector at waystation B is adapted to have the arm 60 brought into engagement with the spring 62 by five current impulses over the line and that it is arranged to have its arm 61 brought into engagement with the spring 64 in response to three impulses over the line. Now in order to operate the signal controlled by the selector at waystation B, the dispatcher starts an impulse transmitter 7, which will first send five current impulses over the line. These five impulses will cause the selector to advance its ratchet wheel 42 five steps, bringing the arm 60 into contact with the contact spring 62 and establishing a low resistance path around the holding magnet 40. This path may be traced from a point 71 of the conductor 72 through arm 60, contact spring 62 and conductor 73 to a

point 74 of the conductor 75. This will put a dead short circuit around the holding magnet 40, and its armature 44 will be retracted. As battery is kept on the line wires 5 and 6 during the release of the holding magnet, the circuit of the stepping magnet 41 will remain intact from line wire 5 through conductors 76 and 77, non-inductive resistance 53, conductor 78, winding of magnet 41, conductor 73, contact spring 62, arm 60 and conductor 72, to line wire 6. The current in this path will maintain the magnet 41 energized until the circuit is opened at the despatching station, which is the next 10 thing that occurs. This opening is only momentary but of sufficient duration to permit the release of the stepping magnet armature and permit the ratchet wheel 42 to return to normal position. Following this 15 momentary opening there will be three more current impulses sent over the line to which the selector will respond, and will have its arm 61 brought into engagement with the contact spring 62. Current will now be held 20 on the line wires for a definite length of time and the holding magnet 40 will be again short circuited in the same manner as above described, and its armature released. The longer arm 61 now being the one in engagement 25 with the contact spring 62, the release of the armature 44 will cause the contact spring 64 to engage contact spring 62, and the normally open bridged bell circuit will be closed. At the same time that 30 the arm 61 has engaged contact spring 62, the contact spring 10 of the impulse transmitter has engaged the surface of the segment 32, causing the contact spring 11 to engage contact spring 33, thereby closing a 35 circuit for the interrupter 34, which may be traced as follows: from one side of battery 14, through conductor 80, armature 36 of interrupter 34, winding thereof, conductor 82, primary of induction coil 35, conductor 38, contact springs 33 and 11 and conductor 45 84 to the other side of the battery 14. The energizing and deenergizing of the interrupter will cause interrupter current to flow in this circuit, which passing through the 50 primary of the induction coil will induce current in the secondary thereof which is superposed upon the line wires. This superposed current will operate the alternating current bell 67 over a circuit which may be 55 traced as follows: from half 85 of the induction coil secondary, through conductor 86, retardation coil 19, one-half of retardation coil 21, line wire 5, conductor 76, condenser 68, alternating current bell 67, conductor 87, contact springs 64 and 62, arm 61, conductor 72, line wire 6, other half of retardation coil 21, retardation coil 20, conductor 88, other half 89 of the induction coil

secondary, conductor 90, armature 16 of impulse relay 13, local contact 18 thereof, conductor 91, battery 14, conductor 92, local contact 17 of impulse relay 13, armature 15 thereof and conductor 93 to half 85 of the induction coil secondary. The opening of the line circuit will release the armature 45 of the stepping magnet 41, which, falling back, will carry the contact spring 64 out of engagement with the contact spring 62 and at the same time permit the ratchet wheel 42 to return to normal position under action 75 of the spring 43, thus opening the circuit for the alternating current bell. Opening of the line circuit also allows the spring 11 to become out of engagement with the spring 33, thereby opening the circuit from battery 80 14 through the interrupter 34.

Since the selector and alternating current bell at waystation C are similar to those at waystation B and are connected in circuit in like manner, and since the position of the contact arms 60 and 61 at each waystation is different, the bell at waystation C may be operated by merely adjusting the sending key for the proper number of impulses to be sent and operating said sending key in the manner above described.

I claim:

1. In a selective signaling system, line wires having a sending station and a waystation connected therewith, a sending key at said sending station, a selector at said waystation controlled by said sending key, an alternating current bell at said waystation, and a local circuit at said sending station including an interrupter; a battery and a normally open contact on said sending key, said sending key in its operation closing said normally open contact and causing interrupted current in said local circuit to be associated with said line wires for operating said alternating current bell.

2. In a selective signaling system, line wires having a sending station and a waystation connected therewith, a sending key at said sending station, a selector at said waystation controlled by said sending key, an alternating current bell at said waystation, a local circuit at said sending station including an interrupter, an induction coil primary and battery, and means controlled by said sending key for closing said local circuit, whereby superposed current is associated with said line wire for operating said alternating current bell.

In witness whereof, I hereunto subscribe my name this 13th day of October, A. D. 1913.

RALPH N. HILL.
